UNITED STATES PATENT OFFICE.

ARTHUR E. CODDING, OF NORTH ATTLEBORO, MASSACHUSETTS.

CIGARETTE-CASE.

1,188,624.

Specification of Letters Patent. Patented June 27, 1916.

Application filed April 19, 1916. Serial No. 92,252.

To all whom it may concern:

Be it known that I, ARTHUR E. CODDING, a citizen of the United States, residing at North Attleboro, in the county of Bristol and State of Massachusetts, have invented certain new and useful Improvements in Cigarette-Cases, of which the following is a specification, reference being had to the accompanying drawings.

10 This invention relates to cigarette cases or holders and has for its primary object to provide a device of this character including a holder proper for supporting cigarettes between the lids of the case, and a 15 single instrumentality operating to urge the lids to their open positions and also maintain the holder centrally therebetween.

It is another object of the invention to provide a case of the type above referred to 20 wherein the holder is constructed in two hingedly connected sections, the said single instrumentality also having the additional function of yieldingly holding the sections in closed position upon the series of cigarettes arranged between the same.

It is a further general object of my invention to materially simplify and improve the construction of devices of the above character, by the provision of a single spring element 25 interposed between the sectional holder and the lid hinge and acting in a single plane to accomplish the above stated desirable result, thus insuring positive and reliable action and eliminating decrease in 30 functional activity of the said spring element owing to the absence of severe tensile strains.

With the above and other objects in view, my invention consists in the novel features 40 of construction, combination and arrangement of parts to be hereinafter more fully described, claimed and illustrated in the accompanying drawing, in which,

Figure 1 is a perspective view showing 45 the case open and the holder disposed in central position; Fig. 2 is a transverse section, the holder being shown in dotted lines swung over from its normal position against one lid of the case; Fig. 3 is a similar view, 50 the holder sections being open; Fig. 4 is a longitudinal section taken on the line 4-4 of Fig. 2; Fig. 5 is a detail perspective view 55 of the spring element; and Fig. 6 is a similar view of one of the holder supporting standards.

It has been found desirable in the manu-

facture of cigarette cases of that type having a holder or container for a plurality of cigarettes, to provide means which will act to maintain the holder in a medial or central position between the lids of the case when the latter is opened so that the cigarettes may be easily removed therefrom or the holder readily filled when empty. Heretofore, this object has been accomplished by 60 an arrangement of wire springs, said springs being disposed upon opposite sides of the holder at the hinged edge of the case and suitably connected to the holder sections and the case so that the springs will operate to 65 urge the lids to their open positions and also centralize the holder between the lids. Such spring elements are subject to considerable strain and their effectiveness is soon impaired. As it is essential to the proper support of the holder that a pair of such 70 springs be provided, arranged upon opposite sides of the hinge connection between the case lids, it will be apparent that such a construction is comparatively expensive. 75

It is, therefore, the purpose of my present invention to dispense with the two separate and distinct sustaining springs for the holder, and to thereby materially reduce the manufacturing cost and provide in lieu 80 thereof a single instrumentality which is so constructed and mounted and arranged with respect to the case lids and the holder that it will serve a three-fold purpose, namely, to urge the case lids to their locking positions, 85 to centralize the holder between the lids, and to yieldably maintain the holder sections in their closed positions. This very desirable end is attained in the following manner: The case is constructed of the two lids or covers 90 5 and 6 which are hingedly connected along one of their side edges, as at 7, in the usual manner, by inserting the pintle 8 through the alternately disposed knuckles 9 and 10 of the respective lids. The lids 5 and 6 are 95 each provided with a continuous inwardly projecting marginal flange or bezel 11 and 12 respectively, and the said flange on the case lid 6 is provided with a notch or recess 13 to receive a suitable latch element 14 100 mounted upon the corresponding edge of the other lid 5.

The structural features of the case above referred to are quite common in the art and constitute no part of the present invention. 105

The holder for the cigarettes comprises the two similar sections 15 which are

stamped out of sheet metal and suitably fluted to provide individual pockets for the reception of the cigarettes. The holder is mounted upon the standards 16, each of said standards being provided upon one of its ends with a sleeve or knuckle 17, as clearly shown in Fig. 6, to receive the hinge pintle 8 of the case. The upper end of each of these standards is also formed with a relatively small sleeve or knuckle 18 which is positioned between the hinge knuckles 19 formed upon one section of the holder 15. Hinge knuckles 20 on the other holder section are arranged in coinciding axial relation with the knuckles 19, and pintles 21 are inserted through these aligned knuckles. Thus, it will be seen that the holder sections are hingedly mounted for relative movement toward or from each other upon the ends of the standards 16.

As shown in detail in Fig. 5 of the drawing, I provide a single flat leaf spring generally designated by the numeral 22. This spring is formed to provide therein a slightly bowed, intermediate or central portion 23, and at each end of said bowed portion of the spring plate a relatively short section 24 extends at a slight inclination with respect to said bowed section, and the terminals 25 of said plate are inclined at a comparatively sharp angle from the portions 24 thereof. In the angular portions 24 of this spring plate, longitudinally extending slots 26 are cut, which are of a length approximately equal to the hinges connecting the two sections of the holder 15. It is to be particularly observed, from reference to Fig. 2 of the drawing, that the spring plate 22 is of a uniform width which is substantially equal to the combined width of the flanges or bezels 11 and 12 on the lids of the case, and is also approximately equal in width to the width of the holder 15.

When the parts of the device are assembled, the knuckles 18 on the standards 16 are inserted through the slots 26 in the spring plate 22 and said knuckles and the hinge knuckles on the lids 5 and 6 connected by means of the pintle 8. The leaf spring 23 which is approximately of a length equal to the length of the lid hinge, bears at the terminals of its inclined end portions 25 upon the adjacent flanges or bezels 11 and 12 of the lids 5 and 6 at the hinge 7 of the case. The intermediate or bowed section 23 of the plate 22 extending between the standards 16, is spaced from the hinge 7 and exerts an upward bearing pressure against the base walls of the sections of the holder 15. When the case is closed and the flanges 11 and 12 are disposed in a plane at right angles to the spring plate 22, said flanges exert a pressure against the extremities of the spring plate and place the same under tension. Thus, when the latch device 14 is

actuated, the terminals of the leaf spring bearing upon the flanges 11 and 12 will immediately urge the lids 5 and 6 to their open positions. This is due to the fact that the spring exerts a downward pressure upon the longitudinal edges of said flanges on opposite sides of the axis of the hinge. Now, it will be apparent that the upward pressure exerted by the central bowed portion 23 of the spring 22 will maintain the holder 15 in a central vertical position between the open lids of the case. As seen in dotted lines in Fig. 2 of the drawing, the holder 15 may be moved over against the inner face of one of the case lids, the standards 16 rocking or pivoting upon the hinge pintle 8 and the spring plate 22 moving with the holder out of bearing contact with the flange of the other case lid. In addition to the functions of the leaf spring 22 above referred to, said spring plate has still a third function, in that it operates by its upward pressure against the base walls of the sections of the holder 15 to yieldingly retain the holder sections in their closed positions and in clamping engagement with the cigarettes arranged between said sections. This will be clearly apparent from reference to Fig. 3 of the drawing and a comparison of the same with Fig. 2. In Fig. 3, the sections of the holder 15 are shown open or spread apart, and it will be observed that each of said holder sections bears upon the medial portion of the leaf spring 22 at the outer edge of its base, whereby it is evident that this portion of the spring plate is placed under additional tension and will immediately act upon the release of the holder sections to again force the same together to their closed positions.

From the above description, taken in connection with the accompanying drawing, it will be seen that I have materially simplified the construction of such cases or holders as now commonly known in the art, and have provided a single resilient metal plate or leaf spring interposed between the pivotally mounted holder and the hinge of the case lids whereby the three-fold purpose previously referred to is attained. This single instrumentality exerts its resilient bearing pressures in the accomplishment of the several enumerated functions, in a single plane. In other words, this single spring plate operates at all times directly in a line with and at right angles to the pivotal axes of the case lids and the holder sections. Consequently, the said operating element is inconspicuous when the case is open, and is not liable to displacement or injury by rough handling in loading the holder with the cigarettes or removing the same therefrom. Furthermore, by so mounting and arranging the single spring plate 22 that it operates upon the several parts in a single

plane and is not bent or distorted from its original form when the case is opened, it will be clearly apparent that greater durability and a maximum of efficiency during long continued use, is procured. In the other devices of an analogous character with which I am familiar, as hereinbefore noted, not only is it necessary to employ two separate and distinct resiliently acting elements connecting the holder sections and the case lids, but when the case is opened the portions of these elements which are connected to the lids are sprung from their normal positions with respect to those portions 10 of the spring elements attached to the holder sections and are thus subjected to possible distortion and considerable tensional strain. In addition to the material advantages in operation above set forth, it is also quite 20 evident that, in view of the extreme simplicity of the single operating element for the several parts of the holder, the device is also preferable to those referred to in the prior art, from an economical standpoint. 25 The manufacturing cost of such cases or holders may obviously be materially reduced over the cost of production of the old type of such devices now upon the market.

In the foregoing description and in the 30 accompanying drawing, I have described and illustrated what I have found to be the preferable form of the spring plate 22 best adapted to the accomplishment of the desired ends, but it is possible that, in the utilization 35 of such a device in connection with cases and holders of other forms than that which I have illustrated for the purposes of this explanation, various changes in shape and form of the several features of the device may be necessary. I, therefore, desire it to be understood that I reserve the privilege of resorting to all such various mechanical changes to which the device is clearly susceptible within the spirit and scope of 40 the appended claims.

Having thus fully described my invention, what I desire to claim and secure by Letters Patent is:—

1. A case of the character described including a pair of hinged lids, a holder pivotally mounted between said lids, and a single spring element acting upon the lids to open the same and also acting upon said holder to maintain the same in a central 55 position between the lids when the latter are open.

2. A case of the character described including a pair of hinged lids, a holder pivotally mounted between said lids, and a single spring element at all times acting in a single plane to urge the lids to open position and maintain the holder centrally therebetween.

3. A case of the character described including a pair of hinged lids, a holder piv-

otally mounted between said lids, and a single spring element interposed between the lid hinge and said holder and acting upon the lids to open the same and also to maintain the holder in a central position between 70 said lids.

4. A case of the character described including a pair of hinged lids, a holder pivotally mounted between said lids, and a single spring element interposed between the 75 lid hinge and said holder and acting in a single plane upon the lids and upon the holder to urge the lids to open position and maintain the holder centrally therebetween.

5. A case of the character described including a pair of hinged lids, a holder consisting of relatively movable opposed members mounted for bodily movement with respect to the case lids, and a single spring element constructed to act upon the case lids 85 and urge the same to open position and to also yieldably retain the holder in a stationary position with respect to the case lids and prevent relative movement of the holder members.

6. A case of the character described including a pair of hinged lids, a holder pivotally mounted for bodily movement with respect to the case lids and consisting of opposed relatively movable clamping members, and a single spring plate acting by its inherent resiliency to first urge the case lids to open position; secondly, maintain the holder in a central position between the case lids; and thirdly, prevent the relative opening movement of the clamping members.

7. A case of the character described including a pair of hinged lids, a holder pivotally mounted for bodily movement with respect to the case lids and consisting of opposed relatively movable clamping members, and a single spring plate arranged between the holder and its pivot acting by its inherent resiliency to first urge the case lids to open position; secondly, maintain the 105 holder in a central position between the case lids; and thirdly, prevent the relative opening movement of the clamping members.

8. A case of the character described including a pair of hinged lids, a holder pivotally mounted on the hinge between the lids, a spring plate acting by its inherent resiliency upon the hinged edges of the case lids to urge the same to their open positions and also upon said holder in a plane at right angles to its pivot to maintain the same in a central position between the open lids.

9. A case of the character described including a pair of hinged lids, a holder pivotally mounted on the hinge between the lids consisting of relatively movable clamping members, a spring plate acting by its inherent resiliency upon the hinged edges of the case lids to urge the same to their open positions and also upon said holder in a 130

- plane at right angles to its pivot to maintain the same in a central position between the open lids and also acting upon the respective clamping members to yieldingly hold the same against relative opening movement.
10. A case of the character described including a pair of hinged lids, a holder pivotally mounted on the lid hinge, and a single spring plate interposed between the holder and the lid hinge and bearing at its extremities upon the hinged edges of the lids to urge the same to their open position, the medial portion of said plate bearing upon the holder to yieldingly maintain the same in a central position between the open lids.
11. A case of the character described including a pair of hinged lids, a holder pivotally mounted on the lid hinge consisting of relatively movable clamping members, and a single longitudinally extending spring plate interposed between the lid hinge and the base of the holder and resiliently acting upon the hinged edges of the lids to urge the same to their open positions and also upon the base of the holder to first maintain the holder in a central position between the case lids and, secondly, to yieldingly hold the clamping members against opening movement.
12. A case of the character described including a pair of hinged lids, a holder pivotally mounted on the lid hinge consisting of relatively movable clamping members, and a longitudinally disposed spring plate interposed between the lid hinge and the base of said holder and resiliently acting throughout its length in a single plane to urge the case lids to open position to retain the holder centrally between the open lids and to yieldingly prevent the opening movement of said clamping members.
13. A case of the character described including a pair of hinged lids, a standard pivotally mounted on the lid hinge, relatively movable holder members hingedly mounted on said standard, and a single spring element embracing the standard and acting by its inherent resiliency first to urge the case lids to open position, secondly, to maintain the holder in central position between the open lids, and thirdly, to prevent the relative opening movement of the hinged holder members.
14. A case of the character described including a pair of hinged lids, a holder pivotally mounted on the lid hinge, and a single spring plate interposed between the lid hinge and the base of the holder and having free end portions bearing upon the hinged edges of the lids to urge the same to open position, the medial portion of said plate bearing upon the base of the holder to maintain the same in a central position between the open lids.
15. A case of the character described including a pair of hinged lids, a holder pivotally mounted on the lid hinge consisting of relatively movable clamping members, and a longitudinally disposed spring plate arranged over the hinge in spaced relation thereto and having a free end portion bearing upon the hinged edges of the lids to urge the lids to their open positions, the medial portion of said spring plate exerting a bearing pressure in a relatively opposite direction against the base of the holder to maintain the same in a central position between the lids.
16. A case of the character described comprising a pair of hinged lids, spaced standards mounted on the lid hinge, holder members hingedly mounted on said standards, and a single spring plate interposed between the lid hinge and the holder members and having slots to receive the standards, the ends of said spring plate bearing upon the hinged edges of the lids and urging the lids to open position and the medial portion of the plate bearing against the holder members to hold the same against relative movement on the standards.
17. A case of the character described comprising a pair of hinged lids, a standard mounted on the lid hinge, a holder mounted upon the standard, and a single spring element interposed between the holder and the lid hinge and acting upon the hinged edges of the lids to urge the lids to open position, said element also co-acting with the holder and said standard to maintain the holder in a central position between the open case lids.
18. In a holder of the character described, a pivoted standard, opposed holder members hingedly mounted upon the standard, and means cooperatively engaged with the standard and holder members to support the standard against pivotal movement and yieldingly hold said members against relative opening movement.
19. In a holder of the character described, spaced pivoted standards, opposed holder members hingedly mounted upon said standards, and means interposed between the pivots of the standards and the holder members operatively engaged with the standards to hold the same against pivotal movement and also operating upon the holder members to yieldingly prevent their relative opening movement.
20. In a holder of the character described, spaced pivotally mounted standards, holder members hingedly mounted upon said standards, and a longitudinally disposed spring plate co-operatively engaged with the standards to yieldingly hold the same against pivotal movement and exerting an upward bearing pressure upon the holder members to yieldingly retain the same in closed position.

21. In a holder of the character described, spaced pivotally mounted standards, holder members hinged upon said standards for relative movement, and a longitudinally disposed spring plate slotted adjacent its opposite ends to receive the respective standards and yieldingly hold the same against pivotal movement, the medial portion of said plate exerting an upward bearing pressure against the base walls of the holder members to 10 yieldingly retain said members in their closed positions.

In testimony whereof I hereunto affix my signature in the presence of two witnesses.
